UNITED STATES PATENT OFFICE

157,095

TEXTILE FABRIC

Howard A. Smith, Fairfield, Conn., assignor to La Resista Corset Co., Bridgeport, Conn., a corporation of Connecticut

Application September 25, 1948, Serial No. 148,771

Term of patent 14 years

(Cl. D92—1)

To all whom it may concern:

Be it known that I, Howard A. Smith, a citizen of the United States, residing at Fairfield, in the county of Fairfield and State of Connecticut, have invented a new, original, and ornamental Design for Textile Fabric, of which the following is a specification, reference being had to the accompanying drawing, forming part thereof.

The figure is a plan view of a textile fabric, showing my new design. The design unit is outlined by broken lines and is repeated as indicated over the fabric.

I claim:

The ornamental design for a textile fabric, substantially as shown and described.

HOWARD A. SMITH.
